UNITED STATES PATENT OFFICE.

FRANK STEVENS, OF PHILADELPHIA, PENNSYLVANIA.

LIQUID-FUEL BURNER.

1,322,269.

Specification of Letters Patent. Patented Nov. 18, 1919.

Application filed December 28, 1918. Serial No. 263,289.

To all whom it may concern:

Be it known that I, FRANK STEVENS, a citizen of the United States, residing at Philadelphia, in the county of Philadelphia and State of Pennsylvania, have invented a new and useful Improvement in Liquid-Fuel Burners, of which the following is a specification.

My invention relates to burners adapted for the combustion of liquid fuels, of which the hydro-carbons, light, such as kerosene, or heavy, such as crude petroleum, are examples.

I have at present pending another application for a burner of similar character, filed May 17, 1918, Serial No. 235,211, in which a rotary fan is used to augment the natural draft resulting from the combustion and in which I employ a rotary bed plate for the combustion chamber, the motive power being a wheel propelled by compressed air. The object of this invention is to provide a burner the draft of which is immensely increased by employing the compressed air in lieu of the wind from a fan wheel, and I accomplish this object by utilizing the exhaust air from the air-wheel, in the pockets of which I introduce orifices, as well as by a system of other and direct distribution of compressed air in various modes as will be more clearly understood by reference to the accompanying drawings, in which—

Figure 1 is a front elevation partly in central section; Fig. 2, a plan view with the wall 22 of the combustion chamber removed and parts broken away to reveal underlying construction; Fig. 3, a plan view of the compressed air system, with the top wall of the air reservoir removed, and Fig. 4, a detail view of my modified air pockets used in connection with the orifice for exhaust.

Similar indices refer to similar parts throughout the several views.

This invention comprises similar elementary members to those described in my prior application with the exception, as stated, of the substitution of the compressed air system for the fan; and, also a slightly different style of fuel fountain.

The fuel is introduced through a vertical supply pipe, 1, capped by a distributing fountain, 2, to a rotatable bed-plate, 3. This plate is secured to a tubular vertical drive shaft, 4, (through which the pipe 1 longitudinally extends) to which is also fixed, immediately beneath the bed-plate, the air-

propelled drive wheel 5. Nozzles 6, from pipes 7, project jets of compressed air from the reservoir 8, in which any desired pressure may be established and maintained through the general supply pipe 9, regulated by valve 10, and connected with any suitable automatic compressor. (Not shown.) Additional regulation is afforded by independent subsidiary valves and gages adapted to greatly enlarge and diversify the control, as will be explained later.

Beneath the drive wheel 5, is positioned a chemical container 11, annular in form—as in my prior application—so as to surround the central shaft and be co-extensive in area with the plate 3. This member, securely retained and supported in the base or standard, 11^a, is utilized as the upper bearing for shaft 4 which has its principal support in a thrust ball-bearing, 12, also secured in the base, 11^a. An annular air-channel, 14, is suitably formed by the wall 15 and the furnace wall 22, which wall becomes very hot when the apparatus is in operation, to supply heated atmospheric air directly to and into contact with the chemical in the container so as to cause this air to absorb vapor therefrom. It is then drawn upwardly by the interior draft between the spokes of the propeller wheel 5, as well as about the periphery thereof.

Compressed air may be admitted to the combustion chamber 21 in any one, or all, of three ways and the proportions thereof regulated, with relation to each source of supply, as well as to the atmospheric air supply, by the system of distributive means and control valves now to be described.

There are three independent routes of supply for the compressed air. First, the air which drives the wheel 5 is supplied through the nozzles 6, jetting into the triangular pockets, 19, annularly arranged in this wheel, and after impinging upon the altitudinal wall of each pocket, is permitted to escape through orifices 16, one of which is located in the upper inclined side near the apex of each pocket. (I herein show the pockets in the form of oblique angled triangle having an obtuse angle in lieu of the right angle shown in my prior application. A very slight inclination away from the base thus produced assists the escape of the air through the orifice 16.) Thus I create a peculiar and effective draft, viz; a rotating series of compressed air streams in which

horizontally moving ascending columns enter the combustion chamber through the perforations 20 in the bed-plate. Second, non-rotating streams of compressed-air are 5 intermittently introduced by pipes 17 from reservoir 8 through the perforations 29 of the bed-plate in a continuous succession of violent puffs resulting from the rapid cutting of the jets by the material parts of the 10 rotating plate. And, third, continuous streams of compressed air are forced into the system through the pipes 18 from reservoir 8^a to the atmospheric air channel 14 so as to play upon the contents of the container 11. By this means additional substantial suction may be caused to act through 15 the channel and increased vaporization of the chemical content produced whereby a chemically charged draft can be amply supplied to the advanced draft produced by the compressed air routes previously described.

Though the agency and manipulation of valves 10^a 10^b and 10^c, with the assistance of 20 gages 30, 30^a and 30^b, various pressures can be adjusted and maintained so as to establish any desired proportions. For, it will be observed that the annular reservoir 8 is divided into three distinct compartments, 8^a, 25 8^b and 8^c, each independently supplied by branches 9^a, 9^b and 9^c, provided, respectively, with the aforesaid individual valves and gages. Thus, for example, the air-through pipe 9^a compartment 8^a, pipe 7, 30 nozzle 6, pocket 19 and orifice 16 (being the driving power and controlling the speed of the bed-plate, as well as a draft element) may well be used as a foundation upon 35 which to base the control, and to the strength of which the central draft from vents 17 and the peripheral drafts from vents 18 may be proportioned with equal, 40 more or less pressure. The atmospheric air supply may be controlled by the dampers, 45 25 in the channel 14. Obviously, they must be shaped, and I have shown the conventional and well-known slideable grille form thus curved. Channel 14 is purposely located as close as possible to the combustion 50 chamber wall 22 in order to raise the temperature of the inflowing air and thereby intensify the vaporizing capacity.

The conical fountain-head, 2, over which the fuel flows after exuding from pipe 1, is 55 located at the center of the combustion chamber 21 above the bed-plate 3 and has, at its base, a gutter 23 in which are made a series of holes, 24, through which the fuel may drip or flow onto the plate to be rapidly 60 spread by the centrifugal force due to the rapid rotation thereof, and almost simultaneously vaporized and consumed.

The operation of this device, which is obvious from the explanatory remarks incident to the foregoing description, is quite

similar to that of my former invention, but, with the additional advantages of producing more intensity of draft, much greater latitude of control, and the entirely new feature of ability to change the speed of the 70 bed-plate without materially altering the amount of draft. In my prior construction the fan producing the forced draft necessarily accompanied the rotating bed-plate and change of speed corresponding 75 affected the air current. In this improvement, however, the only unavoidable change in air with change of speed is that occurring in the streams forming the rotating draft columns from orifices 16 and, if desired, such increase may be substantially neutralized by suitable adjustment of either, or both, of the supplies through vents 17 and 18.

While I show but four of each, it is obvious that the number of nozzles 6, central vents 17 and peripheral vents 18 may be increased or diminished to suit any desired conditions, the only important point to secure the most perfect results in any case being to see that each such member be equidistant from its adjacents. The greater the number of nozzles used will result in increased power and speed as well as increase in draft.

Excepting the propelling blasts from nozzles 6, any one or more of the draft producing means may be greatly reduced or entirely cut off, temporarily or permanently, and, therefore, five distinct systems of draft 100 are available, viz: 1st, atmospheric air through channel 14 in conjunction with compressed air from nozzles 6; 2nd, atmospheric air mixed with compressed air from vents 18 through channel 14 in conjunction with compressed air from nozzles 6: 3rd, atmospheric air through channel 14 in conjunction with compressed air from nozzles 6 and also from vents 17; 4th, atmospheric air mixed with compressed air from vents 18 through channel 14 in conjunction with compressed air from nozzles 6 and also from vents 17; and 5th, compressed air solely from one, two or all three of the sources, to the exclusion of 110 atmospheric air.

As the individual character of each draft element differs varying combinations, and proportions of these drafts produce correspondingly varying results in the combustion chamber, and, consequently with such a choice of selection and combination, such power over the proportions and pressures afforded by the valves, etc., and the perfect and independent speed control over the rotatable bed-plate, the burner is adapted to practically an unlimited field of utility in combustion of liquids. Furthermore, as the fountain 2, may be quickly unscrewed from the pipe, 1, and changed, one appropriate to 125 130

the density of any proposed fuel may always be used, as, for example, one with many small borings for a thin, light fluid, or one with fewer but larger holes for a thick, 5 heavy substance.

For the purpose of illustrating my invention I have described and shown in the accompanying drawings one form thereof which is at present preferred by me, 10 although it is to be understood that the various instrumentalities of which my invention consists can be variously arranged and organized and that my invention is not to be limited to the precise form, arrangement, 15 and organization as herein shown and described, and that I hereby reserve the right to re-organize and re-arrange these instrumentalities within the scope of my claims.

Having thus explained by invention and 20 shown and described a way of constructing and using the same, although without attempting to set forth all the forms in which it may be made or all the modes of its use, I claim:

25 1. A liquid fuel burner comprising a perforated rotatable bed-plate, a fuel fountain above, a rotatable member beneath, orifices in said member alined with certain of the perforations in said bed-plate, means to rotate said plate and said member, and means to project compressed air from said member.

2. A liquid fuel burner comprising a perforated rotatable bed-plate, a fuel fountain above, a series of vents immediately beneath 35 certain of the perforations in said plate, means to rotate said plate, and means to project compressed air from said vents.

3. A liquid fuel burner comprising a perforated rotatable bed-plate, a fuel fountain above, a rotatable member beneath, orifices in said member alined with certain of the perforations in said plate, means to rotate said plate and said member, a series of vents immediately beneath certain other perforations in said plate, and means to project compressed air from said orifices and said vents.

4. In a liquid fuel burner, in combination, a combustion chamber, a chemical container beneath, an atmospheric air channel leading thereto, vents into said channel, and means to project compressed air from said vents.

5. In a liquid fuel burner, in combination, 55 a combustion chamber, a chemical container beneath, an atmospheric air channel leading thereto, vents into said channel, means to project compressed air from said vents, and means to vary and regulate the relative proportions of both atmospheric and compressed air.

6. In a liquid fuel burner, in combination, 60 a combustion chamber, an atmospheric air channel leading thereto, vents in said channel, other vents directed toward said chamber,

ber, and means to project compressed air from all of said vents.

7. In a liquid fuel burner, in combination, a combustion chamber, a chemical chamber beneath, an atmospheric air channel leading 75 thereto, vents in said channel, other vents directed toward said combustion chamber, and means to project compressed air from all of said vents.

8. A liquid fuel burner comprising, a rotatable bed-plate, a fuel fountain above, a rotatable member beneath, orifices in said member, means to rotate said plate and said member, an atmospheric air channel to said plate, vents in said channel, and means to 80 project compressed air from said orifices and said vents.

9. A liquid fuel burner comprising a rotatable bed-plate, a fuel fountain above, a rotatable member beneath, orifices in said member, means to rotate said plate and said member, a chemical container beneath said plate, an atmospheric air channel leading thereto, vents in said channel, and means to project compressed air from said orifices 85 and said vents.

10. A liquid fuel burner comprising a rotatable bed-plate, a fuel fountain above, compressed air vents beneath, means to rotate said plate, an atmospheric air channel 95 leading to said plate, vents in said channel, and means to project compressed air from all of said vents.

11. A liquid fuel burner comprising a rotatable bed-plate, a fuel fountain above, 100 compressed air vents beneath, means to rotate said plate, a chemical container beneath said plate, an atmospheric air channel leading thereto, vents in said channel, and means to project compressed air from all of 105 said vents.

12. A liquid fuel burner comprising a rotatable bed-plate, a fuel fountain above, a rotatable member beneath, orifices in said member, means to rotate said plate and said member, compressed air vents beneath said 110 plate, an atmospheric air channel leading to said plate, vents in said channel, and means to project compressed air from said orifices and from all of said vents.

13. A liquid fuel burner comprising, a rotatable bed-plate, a fuel fountain above, a rotatable member beneath, orifices in said member, means to rotate said plate and said member, compressed air vents beneath said 120 plate, a chemical container beneath said plate, an atmospheric air channel leading to said container, vents in said channel, and means to project compressed air from said orifices and from all of said vents.

14. In a liquid fuel burner, in combination, a combustion chamber, an atmospheric air channel leading thereto, vents in said channel, other vents directed toward said chamber, means to project compressed air 130

from all of said vents, means to vary the relative proportions of atmospheric air with air from the channel vents, and means to vary the relative proportions of both compressed air supplies with the atmospheric air and with each other.

15. In a liquid fuel burner, in combination, a combustion chamber, a chemical container beneath, an atmospheric air channel leading thereto, vents in said channel, other vents directed toward said chamber, means to project compressed air from all of said vents, means to vary the relative proportions of atmospheric air with air from the channel vents, and means to vary the relative proportions of both compressed air supplies with the atmospheric air and with each other.

16. A liquid fuel burner comprising a rotatable bed-plate, a fuel fountain above, a rotatable member beneath, orifices in said member, means to rotate said plate and said member, an atmospheric air channel to said plate, vents in said channel, means to project compressed air from said orifices and said vents, means to vary the relative proportions of atmospheric air with compressed air in said channel, and means to vary the relative proportions of the compressed air from said orifices and from said vents with the atmospheric air and with each other.

17. A liquid fuel burner comprising a rotatable bed-plate, a fuel fountain above, a rotatable member beneath, orifices in said member, means to rotate said plate and said member, a chemical container beneath said plate, an atmospheric air channel leading thereto, vents in said channel, means to project compressed air from said orifices and said vents, means to vary the relative proportions of compressed air and atmospheric air in said channel, and means to vary the relative proportions of the compressed air from said orifices and from said vents with the atmospheric air and with each other.

18. A liquid fuel burner comprising a rotatable bed-plate, a fuel fountain above, compressed air vents beneath, means to rotate said plate, an atmospheric air channel leading thereto, vents in said channel, means to project compressed air from all of said vents, means to vary the relative proportions of atmospheric and compressed air in said channel, and means to vary the relative proportions of the compressed air from each set of vents with the atmospheric air and with each other.

19. A liquid fuel burner comprising a rotatable bed-plate, a fuel fountain above, compressed air vents beneath, means to rotate said plate, a chemical container beneath said plate, an atmospheric air channel leading thereto, vents in said channel, means to project compressed air from both sets of vents, means to vary the relative proportions

of atmospheric and compressed air in said channel, and means to vary the relative proportions of the compressed air from each set of vents with the atmospheric air and with each other.

20. A liquid fuel furnace comprising a rotatable bed-plate, a fuel fountain above, a rotatable member beneath, orifices in said member, means to rotate said plate and said member, compressed air vents beneath said plate, an atmospheric air channel leading to said plate, vents in said channel, means to project compressed air from said orifices and from all of said vents, means to vary the relative proportions of atmospheric and compressed air in said channel, and means to vary the proportions of compressed air from all three sources with the atmospheric air and with one another.

21. A liquid fuel burner comprising a rotatable bed-plate, a fuel fountain above, a rotatable member beneath, orifices in said member, means to rotate said plate and said member, air vents beneath said plate, a chemical container beneath said plate, an atmospheric air channel leading thereto, vents in said channel, means to project compressed air from said orifices and from all of said vents, means to vary the relative proportions of atmospheric and compressed air in said channel, and means to vary the proportions of compressed air from all three sources with the atmospheric air and with one another.

22. A liquid fuel burner comprising a rotatable bed-plate, a fuel fountain above, a rotatable member beneath, orifices in said member, means to rotate said plate and said member, compressed air vents beneath said plate, means to project compressed air from said orifices and from said vents, and means to vary the relative proportions of compressed air from said vents and said orifices respectively.

23. In a liquid fuel burner, a draft system comprising a rotatable burner-plate, perforations therein, and means to project a horizontally rotating series of ascending streams of compressed air through said perforations.

24. In a liquid fuel burner, a draft system comprising a rotatable perforated burner-plate, means to project a horizontally rotating series of ascending streams of compressed air through the perforations therein, and means to cause an annular draft of air to converge into said rotating series.

25. In a liquid fuel burner, a draft system comprising a rotatable perforated burner plate, means to project a horizontally rotating series of ascending streams of compressed air through said perforations therein, and means to cause an annular draft of chemically charged air to intermingle with said rotating series.

26. In a liquid fuel burner, a draft system comprising a rotatable perforated burner plate, means to project a horizontally rotating series of ascending streams of compressed air through the perforations therein, and means to cause a fixed series of ascending streams of compressed air to interlace with said rotating series. 65
27. In a liquid fuel burner, a draft system comprising a rotatable perforated burner plate, means to project a horizontally rotating series of ascending streams of compressed air through the perforations therein, means to cause a fixed series of ascending streams of compressed air to interlace with said rotating series, and means to cause an annular draft of heated air to converge into said interlaced streams. 70
28. In a liquid fuel burner, a draft system comprising a rotatable perforated burner plate, means to project a horizontally rotating series of ascending streams of compressed air through the perforations therein, means to cause a fixed series of ascending streams of compressed air to interlace with said rotating series, and means to cause an annular draft of chemically charged heated air to converge into said interlaced streams. 75
29. In a liquid fuel burner, a draft system comprising a rotatable perforated burner plate, means to project a horizontally rotating series of ascending streams of compressed air through the perforations therein, means to cause a fixed series of ascending streams of compressed air to interlace with said rotating series, and means to cause an annular draft of compressed air to converge into said interlaced streams. 80
30. In a liquid fuel burner, a draft system comprising a rotatable perforated burner plate, means to project a horizontally rotating series of ascending streams of compressed air through the perforations therein, means to cause a fixed series of ascending streams of compressed air to interlace with said rotating series, and means to cause an annular draft of compressed air to converge into said interlaced streams. 85
31. In a device of the character described, in combination, rotatable members to augment combustion and actuating means therefor comprising a drive wheel, pockets annularly disposed therein, nozzles so inclined as to project air-streams into said pockets in a plane parallel with a side thereof, an orifice behind the apex of each of said pockets, and an air reservoir with pressure control appliances to supply said nozzles. 90
32. In a device of the character described, in combination, rotatable members to augment combustion and actuating means therefor comprising a drive wheel, obtuse angled triangular pockets annularly disposed therein, an orifice in the upper wall of each pocket, and means for projecting streams of compressed air into said pockets and through said orifices. 95
33. In a device of the character described, an apparatus combining draft producing and driving utilities, comprising an annular rotatable member, a drive shaft thereto, a series of orifices therein, a corresponding series of pockets therein, nozzles positioned to eject compressed air into said pockets, means to afford a continuous flow of compressed air to said nozzles, and means to vary and control the pressure and volume of the flow. 100
34. In a device of the character described, an apparatus combining draft producing and driving utilities, comprising a drive wheel, a circle of pockets adjacent to the circumference thereof, a circle of orifices equal in number and communicating respectively with said pockets, nozzles positioned to eject compressed air into said pockets, other nozzles positioned to project compressed air between the spokes of said wheel, means to afford a continuous flow of compressed air to all of said nozzles, and means to vary and control the pressure and supply of said air. 105
35. In a device of the character described, an apparatus combining draft producing and driving utilities, comprising a drive wheel, a circle of pockets adjacent to the circumference thereof, a circle of orifices equal in number and communicating respectively with said pockets, nozzles positioned to eject compressed air into said pockets, other nozzles positioned to project compressed air between the spokes of said wheel, still other nozzles positioned to project compressed air horizontally beneath said wheel, means to afford a continuous flow of compressed air to all of said nozzles, and means to vary and control the supply of said air. 110
36. In a device of the character described, a fuel supply fountain comprising a coniform body part, a central opening truncating the apex thereof, a channel encircling the base thereof, divers holes, through said channel, and means to attach said central opening with a fuel supply source. 115

Signed at Philadelphia this fifth day of December A. D. 1918.
